UNITED STATES PATENT OFFICE.

JOSEPH PERSAULT AND THEOPHILE MARQUIS, OF NASHUA, NEW HAMPSHIRE.

RAZOR-SHARPENING MACHINE.

1,082,904.

Specification of Letters Patent.

Patented Dec. 30, 1913.

Application filed March 25, 1913. Serial No. 756,639.

To all whom it may concern:

Be it known that we, JOSEPH PERSAULT and THEOPHILE MARQUIS, citizens of the United States, residing at Nashua, in the county of Hillsboro and State of New Hampshire, have invented new and useful Improvements in Razor-Sharpening Machines, of which the following is a specification.

10 Our present invention pertains to means for sharpening the blades of safety and other razors; and it contemplates the provision of a simple, easily operated and efficient machine for honing and stropping razor and other blades.

15 The invention in all of its details will be fully understood from the following description and claims when the same are read in connection with the drawings, accompanying and forming part of this specification, in which:

Figure 1 is a side elevation of the machine constituting the best practical embodiment of our invention that we have as yet devised. Fig. 2 is a transverse section taken in the plane indicated by the line 2—2 of Fig. 1, looking in the direction indicated by the arrow. Fig. 3 is a detail transverse section taken in the plane indicated by the line 3—3 of Fig. 1, looking in the direction indicated by arrow. Fig. 4 is an elevation of the right-hand end of the machine. Fig. 5 is an elevation, and Fig. 6 an inverted plan of the holder we prefer to employ for safety-razor blades. Fig. 7 is a detail view, partly in elevation and partly in section, illustrative of the feed-means for moving a blade to be sharpened longitudinally of the machine. Fig. 8 is an enlarged detail section showing the arrangement of the holder and its appurtenances relative to the feed-screw. Fig. 9 is a detail of a portion of the mechanism for oscillating the holder. Fig. 10 is a detail view of part of the driving connections, hereinafter specifically referred to.

Similar numerals of reference designate corresponding parts in all of the views of the drawings.

50 The main frame of the machine may be of any construction compatible with the purpose of our invention, though we prefer to have it comprise a suitably supported table,

1, and bearings 2 disposed above and fixedly connected with the table.

Journaled in the bearings 2 and adapted to oscillate about its axis is a longitudinal, hollow shaft 3, longitudinally slotted between the bearings 2, as indicated by 4. It will also be noted by comparison of Figs. 1 and 8, that the shaft 3 is provided with a longitudinal exterior rib 5.

Fixed upon the right-hand end of the hollow shaft 3 is a crank 6 through which the shaft is rocked to and fro about its axis, and mounted on the said shaft 3, intermediate of the bearings 2, is the blade-carrying and manipulating device comprised in our improvements. The said device comprises a body 7 surrounding the shaft 3 and engaged with the rib 5, so as to rock with the shaft and yet be capable of moving thereon in the direction of the length thereof, a bail-shaped standard 8 fixed to and extending from the body 7, an endwise movable plunger 9 guided in the body 7 and extending through the slot 4 in the shaft 3, and also guided in the outer portion of the standard 8 and having a finger-piece 10 at its outer end, and also having an enlargement 11 at a point adjacent the body 7, a coiled spring 12 surrounding the plunger 9 and interposed between the outer portion of the standard 8 and the enlargement 11 so as to yieldingly press the plunger toward the center of the hollow shaft 3, and a threaded nut section 13 carried at the inner end of the plunger 9 and designed to be yieldingly held against and to cooperate with the longitudinal feed-screw 14. The described appurtenances of the holder are clearly shown in Fig. 8, and by reference to said figure, it will be readily understood that by pulling outwardly on the finger-piece of the plunger 9 and against the action of the spring 12, the nut section 13 is disengaged from the feed-screw 14, whereupon the holder can be expeditiously and easily moved lengthwise on the hollow shaft 3 in either direction, and this independently of the feed-screw 14.

When, however, the plunger 9 is released, the spring 12 will operate to hold the nut section 13 in engagement with the thread of the screw 14, and then the holder will depend on the rotation of the screw for its

movement in the direction of the length of the machine.

As best shown in Fig. 8, the holder body 7 is provided with a stem 15, and in the present embodiment of our invention the said stem is designed to occupy a socket 16 in a bail-shaped blade carrier 17; the said blade carrier 17 being detachably connected to the stem 15 through the medium of a set 10 screw 18 that bears in the wall of the socket and is designed to engage and hold the stem 15. See Figs. 1, 5 and 8. Mounted to rock about its axis in the bail-shaped carrier 17 is a shaft 19 that is held against 15 too free rocking movement and also against undue endwise movement by a coiled spring 20. The said shaft 19 is provided with a plurality of studs 21, which are designed to take into the apertures provided in a conventional safety razor blade 22; the said blade 22 being mounted on the said studs 21 and retained in position by a plate 23, Fig. 6. The plate 23 is provided with beveled ends 24, and these are snugly arranged 25 in undercut portions 25 of the shaft 19. By virtue of the arrangement shown in Fig. 6, it will be manifest that the plate 23 will securely hold the blade 22 on the studs 21 of shaft 19, and yet when it is desired to remove the blade to give place to a fresh blade, the plate 23 may, by the exertion of a little pressure, be moved in the direction of its width out of engagement with the shaft 19, whereupon the blade 22 may be readily 35 lifted off the studs 21.

While we prefer to employ the carrier 17 and the described appurtenances thereof, we do not desire to be understood as confining ourselves to the said carrier and its appurtenances, inasmuch as a blade carrier of any other description may be employed in the practical use of our machine without involving departure from the scope of our invention as claimed.

45 The feed-screw 14 is journaled in the end portions of the tubular shaft 3, and is provided at one end with a spur gear 26 through which the feed-screw is continuously rotated during the operation of the machine.

50 Journaled in suitable standards 27 fixed to and rising from the table 1 are honing rolls 28 which are preferably composed of the abrasive substance commonly known as razor grit. The journals 29 of the said rolls 55 28 are provided with band pulleys 30 at their outer ends, as clearly shown in Figs. 1 and 4.

55 Rolls formed of wood and covered with felt and leather in the order named may be employed in our machine for the stropping function without involving departure from the scope of our claimed invention. We prefer, however, to employ for stropping razor blades the leather belts 31, clearly 65 illustrated in Figs. 1 and 2. The said belts

31 have their inner stretches opposed, and they are mounted on upper idler rolls 32, and lower driven rolls 33. At about the proportional distance illustrated below the idler rolls 32, small rolls 34 are opposed to 70 the idle sides of the inner stretches of the stropping belts 31. The said rolls 34 are mounted in carriages 35, and the said carriages are adjusted and adjustably fixed through the medium of suitably mounted 75 screws 36. Consequently it will be manifest that the rolls 34 can be caused to exert greater or less pressure against the inner stretches of the stropping belts. This is 80 advantageous, inasmuch as when a blade is being stropped, the edge of the blade touches the stropping belts at points immediately below the small rolls 34. This contributes to the production of a fine edge on the blade, inasmuch as the portions of the inner 85 stretches of the belts below the rolls 34 are maintained in a taut state, and yet are possessed of flexibility.

In the operation of our novel machine and when the abrasive rolls 28 and the belts 31 90 are driven in the manner hereinafter described, a blade can be first honed and then stropped. In honing the blade, the operator manipulates the plunger 9 so as to disengage the nut section 13 from the feed 95 screw 14, and then moves the body 7 to a point at one end of the pair of rolls 28. The operator then releases the plunger 9 to reestablish engagement between the nut section 13 and the screw 14, whereupon owing 100 to the rotation of the feed-screw, the blade will be caused to traverse from one end of the space between the rolls 28 to the other end of the said space. Incidental to the said traverse and owing to the rocking of the 105 hollow shaft 3, the blade will be oscillated so that first one of its sides will be presented to one abrasive roll 28, and then its other side will be presented to the other abrasive roll 28. At the end of the described 110 traverse of the blade, the operator by manipulating the plunger 9 disengages the nut section 13 from the feed screw 14, and then moves the holder with the carrier 17 and the razor blade 22 endwise of the machine 115 and back to the starting point. He then releases the plunger 9, whereupon the described honing operation will be repeated, and it will be obvious in this connection that the honing operation may be repeated as 120 many times as is necessary to adequately hone the blade. After the honing operation is completed, the plunger 9 is manipulated and the blade holder is adjusted on the shaft 3 and independently of the feed screw 14 125 to place the blade between the stropping belts 31. The plunger 9 is then released and the blade is caused to traverse the space between the belts 31, and during such traverse is oscillated to present it first to one belt 130

and then to the other. It will also be understood here that by returning the holder to the initial point, the operator can cause the blade to traverse the space between the belts 31 as many times as is necessary to produce a fine edge on the blade.

Connected to the crank 6 of the hollow shaft 3 is a pitman 40, Fig. 4, which is connected, in turn, with a spur gear 41 off the center thereof, whereby when the gear 41 is rotated the hollow shaft 3 will be rocked in the manner and for the purpose before described.

Intermeshed with the spur gear 26 is a spur gear 42, Fig. 1, fast on a short shaft 43 which also has a fast band pulley 44. This band pulley 44 is connected through a belt 45 with a pulley 46 fast on a long shaft 47. The said shaft 47 is provided at an intermediate point of its length with a fast sprocket gear 48, and it is also provided with a fast spur gear 49 which latter is intermeshed with the spur gear 41, Fig. 4. Consequently it will be observed that when the shaft 47 is rotated, the hollow shaft 3 will be rocked about its axis and the feed screw 14 will be rotated. The shaft 47 is driven from a drive-shaft 50, best shown in Fig. 3, through a sprocket gear 51 fast thereon, and a sprocket belt 52 mounted on the gears 51 and 48. Obviously the shaft 50 may be driven by any suitable motor which we have deemed it unnecessary to illustrate.

The abrasive rolls 28 are driven from the shaft 47 through the medium of a band pulley 60 fast on said shaft, Fig. 4, and belts 61 mounted on the said band pulley 60 and the band pulleys 30; one of the said belts or bands being crossed as shown, to provide for

its roll turning inwardly and downwardly.

Fixed with respect to the driven rolls 33 of the stropping belts 31 are intermeshed spur gears 65, and by virtue of this it will be observed that when the roll 33 that loosely surrounds the shaft 47 is rotated, both rolls 33 will be rotated and the belts 31 driven in the proper direction.

Fixed on that roll 33 which loosely surrounds the shaft 47 is a sprocket gear 70, Figs. 1 and 3, and connecting the said sprocket gear 70 with a sprocket gear 71 fast on the drive-shaft 50 is a sprocket belt 72.

It will be gathered from the foregoing that rotation of the drive-shaft 50 will be attended not only by endwise movement and oscillation of the means for carrying the razor blade to be sharpened, but will also be attended by rotation of the abrasive rolls 28 and appropriate movement of the belts 31.

We have entered into a detailed description of the construction and relative arrangement of the parts comprised in the present and best practical embodiment of our invention of which we are aware, in order to impart a full, clear, and exact un-

derstanding of the same. We do not desire, however, to be understood as confining ourselves to the said specific construction and relative arrangement of parts, as, in the future practice of the invention, such changes or modifications may be made as fairly fall within the scope of our invention as defined in the claims appended.

Having described our invention, what we claim and desire to secure by Letters Patent, is:

1. In a razor sharpening machine, the combination of opposed sharpening devices separated by an intervening space, means for driving the said sharpening devices, a suitably supported hollow shaft arranged above and parallel to said space and having a longitudinal slot, means for rocking said hollow shaft about its axis, a feed screw extending through and movable independently of the hollow shaft, means for rotating the said screw, blade-carrying means mounted on the hollow shaft to turn therewith and move thereon in the direction of the length thereof, a sectional nut disposed in the hollow shaft and in engagement with the feed screw, a standard fixed on the blade-carrying means, a plunger guided in the blade-carrying means and the standard and connected to the sectional nut and having an enlargement at an intermediate point of its length, and a spring surrounding the plunger and interposed between the enlargement thereof and the standard for yieldingly holding the sectional nut in engagement with the thread of the feed screw.

2. In a razor sharpening machine, the combination of opposed sharpening devices separated by an intervening space, means for driving the said sharpening devices, a suitably supported hollow shaft arranged above and parallel to said space and having at one end a crank, a wheel, means for rotating said wheel, a pitman connected to said crank and also connected to said wheel off the center thereof, blade-carrying means mounted on the hollow shaft to turn therewith and move thereon in the direction of the length thereof, and means for moving the blade-carrying means on the hollow shaft lengthwise of the said shaft.

3. The combination of a suitably supported hollow shaft having a longitudinal slot and an exterior longitudinal rib, means for rocking said shaft, a feed screw extending longitudinally through and rotatable independently of the hollow shaft, means for rotating the said screw, blade carrying means movable lengthwise of the hollow shaft and engaged with said exterior rib so as to turn with the shaft, a nut section carried by said carrying means, and means also carried by said carrying means for yieldingly holding the nut section in engagement with the thread of the feed screw and for

enabling an operator to disengage the nut section from the feed screw.

4. In a razor sharpening machine, the combination of a shaft having fast thereon 5 a spur gear, means for rotating said shaft, lower driven rollers; one of said rollers being loosely mounted on said shaft, means for rotating the roller that is loose on the shaft, intermeshed spur gears connecting the 10 two driven rollers, idler rollers disposed above the driven rollers, stropping belts mounted on the lower driven rollers and the upper idler rollers and separated by an intervening space; abrasive honing rolls separated by an intervening space that is aligned 15 with said space between the stropping belts, means intermediate the said shaft and the

honing rolls for driving the latter by the former, means for carrying a razor blade to be sharpened, means for causing the said carrying means to make traverses of the space between the stropping belts and the space between the honing rolls, and means for oscillating the said carrying-means incidental to the traverse thereof. 20

In testimony whereof we have hereunto set our hands in presence of two subscribing witnesses. 25

JOSEPH PERSAULT.
THEOPHILE MARQUIS.
